UNITED STATES PATENT OFFICE.

ALTON D. HARMON, OF CAMBRIDGE SPRINGS, PENNSYLVANIA.

CALCULATING-MACHINE.

1,136,797.

Specification of Letters Patent. Patented Apr. 20, 1915.

Application filed November 9, 1914. Serial No. 871,125.

To all whom it may concern:

Be it known that I, ALTON D. HARMON, a citizen of the United States, residing at Cambridge Springs, in the county of Crawford and State of Pennsylvania, have invented certain new and useful Improvements in Calculating-Machines; and I do hereby declare the following to be a full, clear, and exact description of the invention, such as will enable others skilled in the art to which it appertains to make and use the same.

This invention relates to calculating machines, for adding and subtracting numerals, which are provided with tablets and slides; and it consists in the novel construction and combination of the parts hereinafter fully described and claimed.

In the drawings, Figure 1 is a front view of a calculating machine constructed according to this invention. Fig. 2 is a cross-section through the machine, taken on the line $x-x$ in Fig. 1. Fig. 3 is a detail view of the back plate of the machine. Fig. 4 is a front view of one of the slides. Fig. 5 is a longitudinal section through the machine, taken on the line $y-y$ in Fig. 1. Fig. 6 is a detail view of one of the carrying signals.

The machine has a tablet or frame the back plate B of which is provided with a series of ribs b which project upwardly from it. These ribs are arranged parallel to each other, and preferably at equal distances apart, and their ends b' serve as stops for the slides.

The slides C have slots c in their backs which slide over the ribs b with very little friction, and stops c' are formed at the ends of the slots for coming in contact with the stops b' of the ribs to prevent the slides from being slid out of the frame and being lost.

Any convenient number of slides C is provided, and six similar slides are shown, and are numbered from 1 to 6 consecutively from right to left. Each slide has a row of 18 stylus holes d and d' formed in it and arranged at equal distances apart. The lower 9 holes d are formed in a shaded or blackened portion D of the slide to distinguish them from the upper nine holes d', but the slide may be otherwise marked in any convenient manner to distinguish between the two series of holes d and d'.

The holes d and d' are arranged on one

side portion of the slide, and its other side portion is provided with a row of index numerals E, from 0 to 9 inclusive. These numerals are arranged at the same distances apart as the stylus holes, the numeral 2 being arranged opposite the bottom stylus hole of the series d.

F is the face plate of the tablet or frame which is secured to the back plate B in any approved way, and which extends over all the slides. In the device illustrated, the back plate has projecting pillars f on its face, and the face plate is secured to these pillars by screws f'.

The face plate has a series of parallel slots g corresponding to the slides 1 to 6, and arranged so as to expose the stylus holes in the slides. The ends g' of the slots g form stops for the stylus or other similar instrument which is inserted in the stylus holes and is operated so as to move the slides longitudinally. The face plate has a series of sight holes h formed in it below the bottom ends of its slots, and arranged in line with the index numerals E on the slides. These sight holes are positioned so that when the cipher 0 on each slide is visible through the sight hole pertaining to the slide, the lowest stylus hole of the series d is opposite the numeral 1 of a series of numerals J marked on the face plate. Each slot has a series of numerals J, 1 to 9 inclusive, marked on it and the numerals of each series are arranged at the same distances apart as the stylus holes in the slides and the index numerals E.

The upper and lower ends of the face plate have flanges k which project forwardly and form handles which are convenient in using the machine. The face plate is formed of thin resilient sheet metal or other material which will spring a little, and indentations n are formed in it for engaging with the stylus holes of the slides. These indentations are preferably pressed in the sheet metal plate at the upper ends of the slots, but any other approved means may be provided for checking the free movement of the slides intermittently, and obliging a small amount of force to be used to manipulate them, so that they do not slide accidentally when the machine is tilted or moved about. These spring projections engage automatically with the stylus holes.

Carrying signals are provided, and a simi-

lar carrying signal is secured behind each bar of the face plate except the left hand one. Each carrying signal is formed of two levers p and s arranged end to end and having their adjacent ends articulated or connected so that the levers move pivotally in opposite directions. The lever p is pivoted to the face plate by a pin p' , and the lever s is pivoted to the face plate by a pin s' , the pivot pins being arranged at the middle parts of the levers.

The upper lever p has teeth t and t' which project laterally from opposite sides of its top end. The lower lever has a tooth w which projects from the left hand side of its bottom end. Fig. 6 shows the signal in its normal position, the tooth t' projecting crosswise of the top of the right hand slot in the path of the stylus, and the teeth t and w being concealed behind the bar of the face plate, which is shown in dotted lines.

The end portion of the stylus is made of a suitable shape to operate the teeth, as well as to engage with the stylus holes. The teeth t and w are signal teeth, and when the stylus is moved to the top of the slot and operates the tooth t' , it turns the levers on their pivots and exposes the signal teeth t and w at the top and bottom of the adjacent left hand slot. When the next slide to the left is moved to register the carrying numeral 1, the stylus strikes the tooth w and restores the signal to its normal position.

The machine may be used both for adding and for subtracting, and as a sample of its use for adding, suppose the numerals 7, 21, and 508 are to be added together. The slides are first placed in the zero position, as shown in Fig. 1. The first numeral 7 is registered by inserting a stylus in the stylus hole of slide No. 1 which is opposite the numeral 7 adjacent to said slide on the face plate, and moving the slide downwardly until the stylus strikes the bottom end of the slot. This will cause the numeral 7 on the slide to be exposed at the left hand sight hole. When the stylus hole to be used is in the series of stylus holes d and in the shaded or blackened portion of the slide, the slide must always be moved downwardly; but when the appropriate stylus hole is in the series d' and in the white portion of the slide, the slide is moved upwardly. Each time a slide is moved upwardly, 1 must be added by means of the next left hand slide.

The numeral 21 is added by registering the 2 with slide No. 2, and the 1 with slide No. 1, in a similar manner to the 7, so that 28 appears at the sight holes.

60 The 508 is added by registering the 5 with the slide No. 3. The cipher 0 does not require to be registered, and the 8 is registered with slide No. 1. As the appropriate stylus hole for registering 8 is in series d' in the white part of the slide, the slide is moved

upwardly until the stylus strikes the top end of the slot and operates the signal. The necessary 1 is added by moving slide No. 2 with the stylus, the stylus being inserted in the stylus hole opposite the numeral 1, and the slide being moved downwardly, and thereby resetting the signal to its normal position. This will cause 536 to appear at the sight holes, which is the correct sum of the numerals 7, 21, and 508.

75 Other numerals are added in a similar manner, and subtraction can be effected by operating the machine in a somewhat reversely similar way. The signals show automatically when carrying numbers are to be added, and also indicate the correct slide to be manipulated.

What I claim is:

1. In a calculating machine, the combination, with a frame provided with a back plate having a series of parallel projecting ribs, and a numbered face plate provided with slots and sight holes; of a series of slides provided with slots in their backs which engage with and slide upon the said ribs, said slides being supported upon the said ribs out of contact with the said back plate and with each other, said slides being also provided with index numerals arranged behind the bars of the face plate and in line with the sight holes.

90 2. In a calculating machine, the combination, with a frame having a face plate provided with parallel slots, and slides movable in the frame and provided with stylus holes; of a carrying signal pivoted under the face plate between two adjacent slots and extending longitudinally of them, said signal having lateral projections at its opposite end portions, one projection being moved into view at one end portion of one slot when the other projection is moved by the stylus at the other end portion of the other slot.

100 3. In a calculating machine, the combination, with a frame provided with a face plate having parallel slots and bars, of a series of slides movable longitudinally in the frame and provided with stylus holes arranged behind the slots and numerals arranged behind the said bars, and signal levers arranged in pairs with their adjacent ends articulated, said signal levers being pivoted behind the said bars and provided with teeth at their opposite end portions adapted to project crosswise of the end portions of the slots, 110 a signal being displayed at one end of one slot each time a lever is operated by the stylus at the other end of the adjacent right hand slot.

115 4. In a calculating machine, the combination, with a frame provided with a face plate having parallel slots and bars, of a series of slides movable longitudinally in the frame and provided with stylus holes arranged behind the slots and numerals ar- 120 130

ranged behind the said bars, signal levers arranged in pairs and having their middle parts pivoted behind the said bars, the adjacent ends of each pair of levers being articulated together, and their opposite ends being provided with teeth adapted to project crosswise of the end portions of the slots, a signal being displayed in one slot

each time a lever is operated by the stylus 10 at one end of the adjacent right hand slot.

In testimony whereof I have affixed my signature in the presence of two witnesses.

ALTON D. HARMON.
